UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEGRAPHIC RELAY.

No. 838,192.

Specification of Letters Patent.

Patented Dec. 11, 1906.

Application filed February 26, 1906. Serial No. 302,985.

To all whom it may concern:

Be it known that I, ISIDOR KITSEE, a citizen of the United States, residing at Philadelphia, in the county of Philadelphia and State of Pennsylvania, have invented certain new and useful Improvements in Telegraphic Relays, of which the following is a specification.

My invention relates to an improvement in telegraphic relays. Its object is to produce a relay which without metallic contact may actuate local translating devices.

The peculiar condition of the submarine cable made it necessary to telegraph with both poles of a source of current, one pole designating a dot and the second pole designating a dash. To receive such impulses and translate the same into record, the ingenious device known as "Thomson's siphon recorder" is used to-day almost generally. This instrument consists of stationary permanent magnets, a movable coil in the region of the lines of force, a soft-iron core in said coil, the coil suspended by cocoon-threads, a bent-glass tube connected to the coil and adapted to follow the movement of this coil, an ink-receptacle in which one end of this glass tube—the real siphon—is immersed, the other end of the siphon in juxtaposition to the moving paper. This siphon has a center position which technically is called the "zero." An impulse of one polarity moves the coil, and therefore the siphon, to the right, and an impulse of opposite polarity moves the coil, and therefore the siphon, to the left.

It is the aim of my invention to utilize this instrument so as to actuate through the same a local circuit, as said above, without any metallic connection.

Referring to the drawings, Figure 1 is a diagrammatic view of a siphon-recorder attached thereto, my device in perspective and a local circuit in diagram. Figs. 2, 3, 4, and 5 are side views of the siphon with disk attached thereto; and Figs. 6 and 7 are plan views showing the disk, in connection with the device, adapted to operate, through the movement of said disk, a local circuit. Fig. 8 is a side elevation, and Fig. 9 a top view, of a sounder.

18 is the siphon-recorder as an entirety, in which 19 is the electromagnet part, 20 the inking part, and 29 the siphon proper. This

siphon has attached to its end a non-conducting part, (here shown in the shape of a disk and designated by 21.) This disk is immersed in a conducting fluid 30, inclosed in a receptacle 22. The receptacle is provided with two pairs of contact-points. One pair is designated by 24 and 25, and the other pair is designated by 27 and 28. 26 is an electromagnetic device provided with the two windings 31 and 32. The winding 32 is connected, through wire 34, with the negative pole of the battery 23 and through wire 35 with contact 28. Contact 27 is connected, through wire 36, with the positive pole of the battery 23. The current, therefore, if these two contacts 27 and 28 are connected, will flow through winding 32 in the direction of the unfeathered arrow. The winding 31 is connected, through wire 33, with the positive pole of the battery 23 and is connected with the other terminal, through wire 37, with contact 25, and contact 24 is connected, through wire 38, with the negative pole of this battery. The current, therefore, if the contact pairs 24 and 25 are closed, will flow through the winding 31 in the direction of the feathered arrow—that is, in opposite direction from the flow of the current in the winding 32.

It is now supposed that the electromagnet 26 is a polarized relay adapted to have its armature move to one contact-point through the flow of a current of one polarity, where the armature remains until the flow of current of opposite polarity removes the same from this contact and moves the same to the opposite contact. In other words, 26 is a polarized relay without a center position, the armature when once moved in one position requiring a current of opposite polarity to be moved in the opposite direction. It is also supposed that the non-conducting part 21 of the siphon 29 is normal in the region of both contact pairs, as is clearly illustrated in Fig. 6. Then the flow of the current will be equally divided between the two circuits embracing the two windings 31 and 32, and as the current flowing in one winding is opposite to the flow of current in the other winding the armature of this instrument will remain in the attained position. It is now supposed that the siphon, with its non-conducting part 21, has moved to the right—that is, out of the region between

the two contacts 27 and 28—and electrically separating to a greater extent the contacts 24 and 25, as is clearly illustrated in Fig. 7. The resistance between 27 and 28 will therefore be lessened and the resistance between 24 and 25 increased. The flow of the current between the two circuits will therefore not be equal, and the greater amount of current will flow through the circuit, including 27 and 28, thereby moving the armature of electromagnet 26 in one direction. If now an impulse of opposite polarity will move the siphon, and therefore the insulating material 21, in the opposite direction—that is, between the contacts 27 and 28—then the ratio of the flow of the current in the two circuits will be reversed, and the armature of 26 will be removed from its former position and will be moved to the opposite contact.

In Figs. 2, 3, and 4 I have shown different modes of providing the siphon proper with the insulating material, preferably in the shape of the disk 21, and in Fig. 5 I have shown one end of the siphon broadened, so as to produce out of this end the insulating material (shown as 21) in the form of a disk. In practice this material 21 consists, preferably, of a disk of very thin mica, if the siphon of to-day is used; but if it is desired this siphon may be replaced by a rod or band of insulating material and integral therewith the disk 21. In this respect the end of the glass rod may be shaped so as to form this disk, or the whole part representing the siphon may be made out of mica or similar material. The mode of connecting the non-conducting material 21 to the siphon proper or the mode of producing out of the end of the siphon the part 21 of necessary dimension is immaterial. It is only necessary that this part shall be in such operative relation to the siphon or its substitute that the movement of this siphon shall be reproduced by its non-conducting part.

In practice the inner space of the receptacle 22 can be very restricted. As the movement of the siphon proper hardly exceeds one-eighth of an inch to one or the other side and the disk does not need to be more than from one to two inches in diameter, it is evident that the length of this receptacle does not need to exceed two and one-half inches. It is desirable that in practice the terminals of the contacts shall be as near together as possible, and I have shown these contacts to be so far apart only for the purpose of better illustration. It is supposed that the thickness of the non-conducting part 21 is about one-twentieth of an inch. Then the contacts of each pair does not need to be farther apart than one-tenth of an inch. As a conducting fluid slightly-acidulated water or a very weak solution of a caustic may be used, I have given these figures for the purpose that persons versed in the art may use the

same in practicing my invention; but it is obvious that these figures and solutions may be varied in accordance with requirements. I prefer the form of a disk, for the reason that the liquid will exert a less retarding movement than if this part 21 were of any other shape.

The employment of this device is of greater advantage in a system wherein true reversals are used. This system differs from the system used to-day in the following: To-day the siphon-recorder assumes normally—that is, when not in use—a zero position and is deflected to the right or left by an impulse of positive or negative polarity. To transmit a dot, an impulse of, say, a positive polarity, is used, and to transmit a dash an impulse of, say, a negative polarity, is used, the impulse of positive polarity deflecting or moving the siphon, say, to the right, and the impulse of negative polarity deflecting or moving the siphon, say, to the left. In its normal position a straight inky line is recorded on the moving paper. A curve to the right or left is recorded through the deflection of the siphon. In this system as some of the letters of the alphabet are symbolized by two or more dashes or dots in succession the siphon must be deflected twice or oftener to one side before being deflected to the opposite side, and as the transmitting of impulses is rapid the siphon has no time to assume its zero position between two impulses in the same direction the movable zero is the result of such action; but where after each positive impulse a negative impulse will follow, or vice versa, the zero position remains always the same—that is, the instrument will always come to rest at its normal zero.

In one of the experiments true reversals were transmitted from "Penzance" and were received at "Canso," and the shape and form of these true reversals clearly indicated that no shifting of the zero took place. The receiving device consisted of the usual siphon-recorder. In no instance deviated one curve from the other curve either in shape or proportion, and the line between the curves was always straight and in the center, thus showing that with these true reversals the fear of the shifting of the zero does not need to be entertained, and considering this behavior of the siphon-recorder as a fact proven by repeated experiments it can be stated that the working of the device, as illustrated and described, is as reliable as the recording through the siphon is to-day.

In the explanation of Fig. 1 it was stated that 26 represents a device, such as a polarized relay provided with two windings. Such a device necessitates a second translating device—such, for instance, as a sounder—and in some instances the interposition of a relay between the receiving device and the translating device proper is not desirable. I

therefore have devised a sounder adapted to be worked directly by the siphon-recorder or an instrument similar in its action. This sounder, as illustrated in Figs. 8 and 9, embraces the two pairs of coils 41 and 42. Each of the coil pairs is provided with a polarized armature, and as the action of the coils as to the battery 23 is of opposite direction the armatures are also polarized in opposite direction. The coil pair 41 is provided with the polarized armature 43, and the coil pair 42 is provided with the armature 44. The sounder of to-day is provided with a spring, whereby the armature, with its lever, is pulled upward when the current ceases to flow in the coil. In the arrangement as illustrated, the spring is discarded and the second pair of electromagnets substituted therefor. The action of this sounder is that when a current is flowing through the coils of 42 the lever is pulled downward, but when a current is flowing through the coils of 41 the lever is pulled upward. The magnetism of the armatures does not need to be very strong, as this magnetism is only provided for the purpose so that the lever shall not fall back when once moved in one position.

I will now describe the operation of the siphon-recorder in connection with the sounder, as illustrated in Figs. 8 and 9. It is necessary, first of all, to state the mode of telegraphing.

In contradistinction from the telegraphing of to-day, wherein for some letters in the alphabet two or more positive impulses or two or more negative impulses are transmitted over the line, the principle of my mode of telegraphing consists in transmitting invariably a negative impulse after a positive, or vice versa, and consists also therein that each impulse is of the same duration and intensity, so that the electric condition of the cable remains practically the same for the whole working time, and the shifting of the zero is out of the question. I transmit one impulse of, say, positive polarity to bring the instrument in the cable-circuit to a position so as to close a local circuit containing a translating device, and this translating device is of such a structure that it has to remain in its closed position till an impulse of, say, negative polarity is transmitted over the line, whereby a second local circuit is closed, altering the position of the translating device in a manner so as to place the same in a so-called "open position" or a position indicating a space.

It is supposed that the line is idle, no impulse flowing over the same. In this state the siphon or similar part of the receiving device inserted in the cable is at the zero position. Through this position the lower or, as I call it, the "tail" part of the siphon is centered between the two contact pairs. It is also supposed that the last impulse which was

flowing over the line before the state of idleness was reached was a negative impulse—that is, an impulse which actuated the electromagnets of the sounder in a manner so as to produce the upper stroke in the lever of said sounder. The lever will therefore have to remain in this position during the whole part of the idleness of the cable. It is now supposed that a positive impulse is transmitted over the line deflecting the tail end of the siphon, so that a greater amount of current will flow through the coil pair 42, whereby the lever of the sounder is pulled downward, producing the so-called "downstroke." The impulse transmitted over the cable is only momentary, and the siphon will, as soon as this impulse has passed, resume its center position, whereby the current-flow in both circuits of the sounder is made equal. No force is therefore present to remove the lever from its upper position, and the same will remain there till a negative impulse will energize the other coil pair so as to produce a downward movement of the lever of this sounder. Now it is supposed that the operator desires to transmit a dot. He transmits a positive impulse and in a short space of time a negative impulse. Through the sending of the first impulse the lever of the sounder will give a downstroke, and through the sending of the second impulse the lever will give an upper stroke, and as between these two strokes a short time elapses, the receiving operator will translate these two strokes as a dot. In transmitting a dash the operator first sends a positive impulse over the line and after a period of more than one unit of time a negative impulse, and the sounder will work in the same manner as if a dash would have been sent over the line—that is, the lever will remain in its downward position for a length of time equal to the time denoting a dash.

I have illustrated and described the device as employed to-day in cable telegraphy, not changing any part of this device with the exception of the condition of the insulating disk, so that the proper officers shall be enabled to receive or relay impulses transmitted over a cable with the aid of an instrument, the working of which they are familiar with. It is obvious that this instrument can at one and the same time record as well as translate in sound the received impulses.

I have described my invention in connection with a siphon-recorder, the same being to-day centered or having what is technically called the "zero position." This position is due to a small weight and sometimes to a light spring holding the siphon in the position aforesaid. Should this weight or spring be removed, then the siphon would rest side-wise to left or right in accordance with the movement of the coil.

It is obvious that any electromagnetic de-

vice with or without a center position may be used with this my invention, the siphon-recorder, as stated above, being preferred because the same was found efficient after an 5 experience of many years.

Having now described my invention, what I claim as new, and desire to secure by Letters Patent, is—

1. A siphon-recorder, a non-conducting 10 tail at one terminal of said recorder, a conducting liquid in which said tail is partly immersed, terminals of electric circuit containing 15 an electromagnet reaching in said liquid, the non-conducting tail adapted to move in the region between said terminals and to move out of said region in accordance with the impulse actuating said siphon.

2. A receiving device, such as a siphon-recorder, a non-conducting tail for the movable 20 part of said device, a receptacle, a conductive liquid for said receptacle, two pairs of contacts reaching in said liquid, an electromagnetic device, two windings for said device, a source of current, said source connected to 25 one winding in opposition to the second winding, the circuit of one winding connected to one pair of said contacts, and of the second winding to the second pair of contacts; the non-conducting tail reaching in said liquid, said tail adapted through its movement 30 to increase or decrease the resistance between the two contacts of one or the other of the contact pairs.

3. An electric relay comprising a receiving 35 device, such as a siphon-recorder, a non-conducting tail for the movable part of said device, a conducting liquid, wherein said tail is immersed, terminals of two circuits in contact with said liquid, means to center the tail 40 between the two pairs of contacts and means

to move said tail out of the region between one pair of said contacts and farther into the region of the other pair of contacts.

4. In combination with an electric cable, a receiving instrument, such as a siphon-recorder, a non-conducting body at the terminal of the siphon, a conducting liquid, terminals of an electric circuit in contact with said liquid; the non-conducting body adapted to move in and out of the region of said terminals, a local circuit for said terminals, a translating device and source of current for said circuit, the movement of said non-conducting body adapted to vary the flow of current in said translating device. 55

5. In combination with an electric cable, a receiving device adapted to open and close a local circuit embracing a source of current, a translating device and conducting liquid, the receiving device provided with means, immersed in said liquid, to vary the flow of the current in said translating device through the changing of its position in said liquid. 60

6. In cable telegraphy, a receiving device, such as a siphon-recorder, a conducting liquid, two pairs of terminals operatively related to said liquid, an electric circuit for each pair, a source of current and translating device for said circuits and means operatively related to the receiving instrument to vary 65 the flow of the current in said circuits, in accordance with the movement of the movable part of said receiving device. 70

In testimony whereof I affix my signature in presence of two witnesses.
